United States Patent Office.

FRANCIS M. PATTERSON AND HENRY P. MILLER, OF SEYMORE, INDIANA.

Letters Patent No. 105,242, dated July 12, 1870.

IMPROVED HARNESS-MAKERS' EDGING-TOOL.

The Schedule referred to in these Letters Patent and making part of the same.

To whom it may concern:

Be it known that we, FRANCIS M. PATTERSON and HENRY P. MILLER, of Seymour, in the county of Jackson and State of Indiana, have invented a new and useful Improvement in Harness-makers' Edging-Tool; and we do declare that the following is a true and accurate description thereof, reference being had to the accompanying drawing and to the letters of reference marked thereon, and being a part of this specification, in which—

Figure 1 is a perspective view of our cutting-tool.
Figure 2 is an end view of the same, with reversible guide.

Figure 3 is a longitudinal section on the line $z z$ in fig. 1.

Like letters refer to like parts in each figure.

The nature of this invention relates to the construction of an edging-tool, especially designed for the use of saddlers and harness-makers, for the purpose of "taking down" or cutting off the edges on leather straps for raised work in harness-making. This work, which is now done with the round knife, is a very tedious and difficult operation, which this device will be found to obviate.

The invention consists in an arched knife properly secured to a metallic frame, and in such a manner that it may be easily removed for the purpose of being sharpened, in combination with guides within which are inserted reversible gauge-blocks, by means of which straps of various width and thickness may be operated upon.

In the annexed drawing—

A represents an arched or angular knife, which is secured to the cast metallic frame B at the front end thereof, said knife having its arched portion uppermost, and extending across said frame, at right angles

with the sides thereof, and presenting its cutting-edge to the rear.

The frame B has a base which rests upon and is secured to a proper table or board, and two vertical sides, B', facing each other, and extending in parallel lines back from said knife for a suitable distance, serving as guides for the reversible gauge-blocks herein-after described.

C are reversible gauge-blocks, the upper and lower sides of which are provided with projecting ribs or guides D, of varying distances apart, so as to accommodate various widths of straps, and guide them to the center of the knife, the angles of which will cut off the opposite edges of the strap in its passage.

These blocks, of which there may be a series, to accommodate all the required widths of straps to be operated, are held in position, when in use, by being placed between the prolongations B' of the frame.

The operation of this device is very simple. Select the gauge-block whose width between the guides or ribs corresponds to the width of the strap, and place it between the metallic prolongations of the frame, taking care not to push it up to the knife until the end of the strap has been passed under the knife. Then push the gauge-block up to the knife and draw the strap through.

What we claim as our invention, and desire to secure by Letters Patent, is—

The angular knife A, in combination with the metallic frame B, provided with guides B', and the gauge-blocks C, provided with ribs D, when constructed and arranged as described, and for the purpose set forth.

F. M. PATTERSON.
H. P. MILLER.
